CLAIM

The ornamental design for a container with attachable dust pan and dusting brush, as shown and described.

DESCRIPTION

FIG. 1 is a front, right side perspective view of a container with attachable dust pan and dusting brush showing my new design in which the dust pan and dusting brush are both arranged on the container;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front, right side perspective view of a container with attachable dust pan and dusting brush showing my new design without the dust pan and dusting brush attached to the container, the front, rear, left side and right side views being ascertainable from this view together with other views shown herein;

FIG. 9 is a top plan view thereof;

FIG. 10 is a bottom plan view thereof;

FIG. 11 is a front, right side perspective view of a container with attachable dust pan and dusting brush showing my new design with the dust pan but without the dusting brush attached to the container, the front, rear, left side and right side views being ascertainable from this view together with other views shown herein;

FIG. 12 is a top plan view thereof; and,

FIG. 13 is a bottom plan view thereof.

The dust pan and/or brush are omitted in FIGS. 8-13 for clarity of illustration.
